CLAIM

The ornamental design for a vanity bowl, substantially as shown and described.

DESCRIPTION

FIG. 1 is a front elevational view of the vanity bowl showing my new design;

FIG. 2 is a top plan view thereof;

FIG. 3 is a right side elevational view thereof, the left side being a mirror image of the side shown;

FIG. 4 is a cross sectional view taken on line 4—4 of FIG. 1; and

FIG. 5 is a cross sectional view taken on line 5—5 of FIG. 3.

Fig. 1.

Fig. 2.

Fig. 3.

Fig. 4.

Fig. 5.
